UNITED STATES PATENT OFFICE

152,486

DESIGN FOR A COMBINED RING AND
PERFUME CONTAINER

Elaine Guthrie Lorillard, Providence, R. I., assignor to Ostby & Barton Company, Providence, R. I.

Application September 17, 1948, Serial No. 148,629

Term of patent 7 years

(Cl. D45—10)

To all whom it may concern:

Be it known that I, Elaine Guthrie Lorillard, a citizen of the United States of America, residing in Providence, county of Providence, and State of Rhode Island, have invented a new, original, and ornamental Design for a Combined Ring and Perfume Container, of which the following is a specification, reference being had to the accompanying drawing, forming part thereof.

Fig. 1 is a front perspective view of a combined ring and perfume container, showing my new design.

Fig. 2 is a perspective view of the opposite side of the combined ring and perfume container from that shown in Fig. 1, with the cap of the container element in a separate position.

I claim:

The ornamental design for a combined ring and perfume container, substantially as shown.

ELAINE GUTHRIE LORILLARD.
